UNITED STATES PATENT OFFICE.

STEPHEN BALKWILL, OF CLEVELAND, OHIO.

RAILWAY-RAIL CONNECTION.

Application filed July 21, 1922. Serial No. 576,593.

To all whom it may concern:

Be it known that I, STEPHEN BALKWILL, a citizen of the United States, residing at Cleveland, in the county of Cuyahoga and 5 State of Ohio, have invented a certain new and useful Improvement in Railway-Rail Connections, of which the following is a full, clear, and exact description.

This invention relates to rail connections 10 capable of use in railway crossings, frogs, rail joints or splices and for other purposes.

It is an object of the invention to provide a connection which is yieldable and in which the bolts cannot be tightened beyond a safe 15 limit.

A further object is to provide a yieldable connection in which the nuts are locked against being worked loose or unscrewing by the vibration caused by passing trains.

20 A further object is to provide a crossing structure in which yielding connections are provided between the parts thereof, the yielding members being of ample strength to withstand the strains to which they are 25 subjected in use and to maintain the parts in proper alignment.

Other objects will be apparent from the following description and the annexed drawings.

30 The annexed drawings and following description set forth in detail certain means embodying my invention. The disclosed means, however, constitute but a few of the various mechanical forms in which the principle of the invention may be employed.

Reference should be had to the accompanying drawings forming a part of this specification in which Fig. 1 is a fragmentary plan view of a crossing embodying the 40 invention; Fig. 2 is a section on line 2—2 of Fig. 1; Fig. 3 is a fragmentary side elevation of a connection from the side on which the pressure bar is applied showing the ratchet nut lock; Fig. 4 is a section on line 45 4—4 of Fig. 3; Fig. 5 is a fragmentary side elevation of a pressure bar showing a modified form of ratchet nut lock; Fig. 6 is a transverse section through the pressure bar shown in Fig. 5; Fig. 7 is a fragmentary side elevation showing the bolt head socket; Fig. 8 is a side elevation of a rail joint; Fig. 9 is a transverse section through the joint shown in Fig. 8; Fig. 10 is a view 50 similar to Fig. 9 showing the position of the nut with respect to the pressure bar when

given an eighth turn from the position shown in Fig. 9; Fig. 11 is a sectional view showing a modified form of nut lock.

The present invention has application particularly to rail connections employing 60 pressure bars which are pressed outwardly from the rail against the nuts or bolt heads by springs. The main improvements contemplated by the present invention consist of the application of supplementary springs 65 in addition to those through which the bolts pass to increase the spring pressure and to obtain a connection of greater strength, and the application of suitable stops and nut locks to prevent the nuts on the bolts from 70 unscrewing from the bolts. These improvements may be used singly or jointly but are most advantageously used together. For convenience these improvements are shown in Figs. 1 to 7 of the drawing as applied to 75 an articulated crossing such as that covered by my Patent No. 1,233,437 granted July 17, 1917.

Referring to the accompanying drawings, Fig. 1 shows a crossing structure comprising angle members 1 formed with rail-tread portions 2 adapted to abut against and align with rails 3 of intersecting tracks and U-shaped crossing members 4 secured together by the angle members 1 and having tread 80 portions 5 which align with the rails 3 of the tracks and the tread portions 2 of the angle members 1. The crossing members 4 have rearwardly extending arms 6 which extend alongside the tread portions 2 of the angle members and the abutting ends of the rails 3 forming guard rails and also serving as splice bars for connecting the ends of the rails 3 to the angle members 1. Inside the tread portions 5 of the crossing members 4 85 are guard rails 7 which may be integral with the members 4 or detachably secured to the members 4. Pressure bars 8 are secured alongside of the rearwardly extending arms of the angle and U-shaped crossing 90 members and pressure bars 9 are secured alongside of the track forming portions of the U-shaped crossing members 4. Threaded bolts 10 having integral heads 11 extend through the angle members 1, rails 3, arms 105 6 and pressure bars 8. Other bolts 10 extend through the angle members 1, the arms 6 and the pressure bars 8 beyond the end of the rails 3. For securing the guard rails 7 in place the bolts extend through crossing 110

members 4, guard rails 7 and pressure bars 9. It is desirable that suitable means be provided to hold the bolts against rotation. This may be accomplished in various ways 5 as well understood in the art. As shown herein, sockets 12 are formed in the outer face of the part against which the heads 11 of the bolts bear in which the heads 11 fit and are held against rotation. Nuts 13 10 which may be of any suitable shape and which, for purposes of illustration, have been shown square, are secured upon the threaded ends of the bolts 10 outside the pressure bars 8 and 9. Coil springs 14 are 15 positioned upon the bolts 10 between the pressure bars 8 and the arms 6 and also between the pressure bars 9 and guard rails 7. To provide against unscrewing of the nuts 13 and overtensioning of the bolts 10, I 20 provide nut locking projections or stops either integral with the pressure bar or upon washers nonrotatably secured upon the outer face of the pressure bar. These stops may be either single or plural and when plural 25 their number corresponds to the number of facets on the nuts. These nut locking stops or projections may be formed to act as one way ratchets for the nut as shown in Figs. 2, 3 and 4, or as two way ratchets as shown 30 in Figs. 5 and 6. As shown in Figs. 2, 3 and 4, ratchet lugs 15 are formed integrally upon the outer faces of the pressure bars about each of the bolt holes forming between them a socket between which the nuts 13 are 35 adapted to fit. In one position of the nut the lugs 15 lie just outside and closely adjacent the side edges of the nut. The lugs 15 are inclined from end to end in one direction and the inner face of the nut is preferably 40 slightly rounded so that upon rotation of the nut in a direction to tighten it upon the bolt, the corners of the nut will ride up along the inclined faces of the lugs 15 forcing the pressure bar bodily inwardly. After 45 each quarter turn the pressure bar springs back and the nut lies within the socket formed by the lugs 15. The direction of the inclined face of the lugs 15 is such that the nut may be turned by means of a wrench 50 in a direction to tighten the bolt but the nut cannot be turned in a reverse direction unless the pressure bar is first forced bodily inward by means of a suitable tool.

In order to obtain greater spring pressure 55 between the pressure bar and rail additional coil springs 16 may be interposed between the inner face of the pressure bar and the track member to which it is applied suitable means being provided to hold the coil 60 springs 16 in position. As shown in Fig. 4 positioning lugs 17 which may be formed integrally with the pressure bar 8, extend inwardly from the inner face thereof and project into the coil springs 16. The pressure bars 8 and 9 are preferably in the form 65

of channel bars with inwardly extending flanges forming a housing for the bolt carried springs 14 and supplemental springs 16. In Figs. 5 and 6 a modified form of ratchet lug 15^a is shown. The outer faces of the lugs 15^a are inclined outwardly from both ends toward the center so that the nut 13 can be rotated in either direction by means of a wrench, the lugs 15^a, however, serving to effectually lock the nut 13 from working loose, due to the vibrations to which it is subjected in use.

In either of the modifications above described, the pressure bar is permitted to spring back slightly after the final turn on 80 the nut relieving slightly the tension upon the bolts 10.

Where rigid connections are employed it often happens that the nuts are drawn too tight placing the body of the bolt under excessive tension so that it is not able to resist the violent impacts to which it is subjected.

The breaking of bolts due to this cause is avoided by the present invention due to the yielding connection and to the action of 90 the ratchet lock.

In Figs. 8, 9 and 10 I have shown the invention applied to an ordinary rail joint in which the rails 18 are connected by splice bars 19 and 20 of an old and well known 95 type.

An angle pressure bar 21 is secured outside the splice bar 20 and bolts 23 extend through the splice bar 19, rail 18, splice bar 20 and pressure bar 21. The 100 splice bar 19 is formed to provide sockets for the heads 23 of the bolts whereby the bolts are held against rotation and coil springs 24 are interposed between the splice bar 20 and the pressure bar 21. A washer 105 plate 25 which may be in the form of a rolled channel bar is secured against the outer face of the pressure bar 21 and has short outwardly extending flanges which project on opposite sides of nuts 26 which are screwed upon the ends of the bolts 22. The inner faces of the nuts 26 are preferably slightly rounded so that as the nut is rotated the corners thereof will ride up upon the flanges of the washer bar 25, as shown 110 in Fig. 10. The flanges of the washer bar 25 in this modification perform the same function as the ratchet lugs 15 or 15^a in the modifications heretofore described.

In Fig. 11 a modified form of nut lock 115 is shown in which a channel washer 27, which may be in the form of a bar extending the whole length of the pressure bar or may be simply in the form of a washer for a single bolt, has inwardly extending flanges 120 fitting over the upper and lower edges of the pressure bar whereby it is held against rotation with the nut. The washer 27 has a lug 28 with an inclined outer face engaging the inner side of the nut 29, the nut 130

29 being provided with an inclined inner face, the inclination of which corresponds to the inclination of the lug 28.

Upon rotation of the nut 29 the pressure bar is alternately forced inwardly and permitted to spring back as the nut 29 is rotated. When the inner face of the nut 29 is in full engagement with the outer face of the lug 28, the nut is effectively held 10 against working loose.

Having described my invention, I claim—

1. In a railway rail connection, the combination with the rail, of a rigid side bar secured against the side of the rail, a plurality of bolts passing through the rail and side bar, each of said bolts having a head and a threaded end adapted to receive a nut, means for holding said bolts against rotation, a pressure bar through which the 20 threaded end of the bolts extend, and springs interposed between said bars, said pressure bar having a rigid projection adjacent each of the bolt holes, each projection having an inclined face engageable with the nut.

2. In a railway rail connection, the combination with the rail, of a rigid side bar secured against the side of the rail, a plurality of bolts passing through the rail and side bar, each of said bolts having a head 30 and a threaded end adapted to receive a nut, means for holding said bolts against rotation, a pressure bar through which the threaded ends of the bolts extend, and springs interposed between said bars, said 35 pressure bar having an integral projection at one side of each of the bolt holes, said projection having an inclined face adapted to be engaged by the nut.

3. In a railway rail connection, the combination with the rail, of a rigid side bar secured against the side of the rail, a plurality of threaded bolts passing through the rail and side bar and held against rotation with respect thereto, a pressure bar through 45 which the threaded ends of the bolts extend, nuts upon the threaded end of the bolts, and springs interposed between said bars, said pressure bar having rigid projections lying beside the edges of the nuts in one position 50 of the nuts and engageable with the inner face of the nuts upon rotation thereof.

4. In a railway rail connection, the combination with the rail, of a rigid side bar secured against the side of the rail, a plurality 55 of threaded bolts passing through the rail and side bar and held against rotation with respect thereto, a pressure bar through which the threaded ends of the bolts extend, nuts upon the threaded ends of the bolts, and springs interposed between said bars, said pressure bar having a plurality of rigid 60 projections on its outer face lying beside the edges of the nuts, said projections having inclined faces engageable with the corners 65 of the nuts upon rotation thereof.

5. In a railway rail connection, the combination with the rail of a rigid side bar secured against the side of the rail, a pressure bar upon the outer side of said side bar, a plurality of clamping bolts extending 70 through said rail and bars, coil springs surrounding said clamping bolts and interposed between said bars, and a supplemental spring in addition to those surrounding the bolts interposed between said bars. 75

6. In a railway rail connection, the combination with the rail, of a rigid side bar secured against the side of the rail, a pressure bar upon the outer side of said side bar, a plurality of clamping bolts extending 80 through said rail and bars, coil springs surrounding said clamping bolts and interposed between said bars, and additional coil springs interposed between said bars, said pressure bar having positioning lugs upon 85 its inner face engaging the outer ends of said additional springs.

7. A railway crossing structure, comprising angle members adapted to be secured to the ends of the rails of the intersecting 90 tracks and having angularly disposed tread forming portions adapted to be aligned with the treads of the rails of the tracks, U-shaped crossing members, each having a tread forming portion adapted to be aligned 95 with a rail of one of the tracks, and having rearwardly extending arms each lying alongside the joint between an angle member and its aligned track rail, a pressure bar extending along the inner side of each of 100 said arms, bolts extending through the rails and angle member, the rearwardly extending arms and the pressure bars, and springs interposed between said arms and said pressure bars. 105

8. A railway crossing structure, comprising angle members adapted to be secured to the ends of the rails of the intersecting tracks, and having angularly disposed tread forming portions adapted to be aligned with the treads of the rails of the tracks, U-shaped crossing members each having a tread forming portion adapted to be aligned 110 with a rail of one of the tracks and having rearwardly extending arms each lying 115 alongside the joint between an angle member and its aligned track rail, a pressure bar extending along the inner side of each of said arms, threaded bolts extending through the rails and angle member, the rearwardly extending arms and the pressure bars, means for holding said bolts against rotation, nuts engaging the threaded ends of said bolts outside said pressure bars, springs interposed between said pressure 120 bars and arms, and rigid ratchet lugs carried by said pressure bars and engageable with said nuts.

9. A railway crossing structure, comprising angle members adapted to be secured to 130

the ends of the rails of the crossing tracks, and having angularly disposed tread forming portions adapted to be aligned with the treads of rails of the tracks, U-shaped crossing members, each having a tread forming portion adapted to be aligned with a rail of one of the tracks and having rearwardly extending arms, each lying alongside the joint between an angle member and its 10 aligned track rail, a pressure bar extending along the inner side of each of said arms, bolts extending through the rails and angle members, the rearwardly extending arms and the pressure bar, coil springs mounted 15 on each of said bolts and interposed between

the pressure bars and arms, and additional springs interposed between said bars and arms.

10. In a railway rail connection, the combination with a rail, of a pressure bar along- 20 side the rail, threaded bolts passing through said rail and bar, springs interposed between said rail and bar, means for holding said bolt against rotation, nuts on said bolts on the outer side of said bar, and rigid 25 ratchet lugs on said bar engageable with said nuts.

In testimony whereof, I hereunto affix my signature.

STEPHEN BALKWILL.
